UNITED STATES PATENT OFFICE.

CHARLES W. WESTON, OF PAMPA, TEXAS.

DESIGN FOR A CHAIR.

Application filed June 13, 1927. Serial No. 22,411. Term of patent $3\frac{1}{2}$ years.

To all whom it may concern:

Be it known that I, CHARLES W. WESTON, a citizen of the United States, residing at Pampa, in the county of Gray and State of Texas, have invented a new, original, and ornamental Design for a Chair, of which the following is a specification, reference being had to the accompanying drawing, forming a part thereof.

I claim:

The ornamental design for a chair, as shown.

CHARLES W. WESTON.
